UNITED STATES PATENT OFFICE.

HENRY WILSON MORROW, OF LISBON, OHIO.

BOX-LID HOLDER.

No. 922,611.

Specification of Letters Patent.

Patented May 25, 1909.

Application filed April 30, 1908. Serial No. 430,142.

To all whom it may concern:

Be it known that I, HENRY W. MORROW, a citizen of the United States, residing at Lisbon, in the county of Columbiana and State 5 of Ohio, have invented a new and useful Box-Lid Holder, of which the following is a specification.

The invention relates to improvements in box lid holders.

10 The object of the present invention is to improve the construction of box lid holders, and to provide a simple, inexpensive and efficient device, designed particularly for use on cigar boxes, and adapted to enable the lids of 15 a plurality of boxes to be all arranged at the same angle, or at any desired angle to afford the best display of the goods.

A further object of the invention is to provide a box lid holder, adapted to rigidly connect a box and its lid to enable the dealer to pick a box up and handle the same by the lid, in lifting the box out of and replacing it in a show case, or in handing a box to a customer.

25 The invention also has for its object to provide a box lid holder, adapted to form a firm brace for the box and the lid to prevent the same from breaking at the hinge joint and causing injury to the contents of the box.

30 With these and other objects in view, the invention consists in the construction and novel combination of parts hereinafter fully described, illustrated in the accompanying drawing, and pointed out in the claims hereto 35 appended; it being understood that various changes in the form, proportion, size and minor details of construction, within the scope of the claims, may be resorted to without departing from the spirit or sacrificing 40 any of the advantages of the invention.

In the drawings:—Figure 1 is a perspective view of a box lid holder, constructed in accordance with this invention and shown applied to a box. Fig. 2 is a perspective view of the box lid holder detached. Fig. 3 is an enlarged detail sectional view, illustrating the construction of the lower clamp.

45 Like numerals of reference designate corresponding parts in all the figures of the drawing.

50 The box lid holder, while designated principally for use on cigar boxes, is adapted to be applied to all kinds of boxes employed for displaying merchandise, and it is designed to 55 be constructed in various sizes to adapt it to the character of box lid to be held. It is

constructed of a single piece of wire, or other suitable material, and it consists of a straight inclined brace 1, an upper resilient clamp 2 and a lower clamp 3. The lower clamp engages the end wall 4 of a box at the upper edge thereof, and the upper clamp 2 engages the lid 5 at the adjacent end thereof, and the brace is arranged at an inclination and extends upwardly from the end 4 to the back 5, 60 as clearly shown in Fig. 1 of the drawing. The brace is adapted to be arranged at different inclinations to support the lid of the box at different angles.

The upper resilient clamp, which is disposed transversely of the brace, is located beyond the upper end thereof and is approximately U-shaped, the wire being bent into substantial U-shape, as clearly shown in Fig. 2 of the drawing. The outer or upper 70 side or jaw of the clamp is provided with a curved extension 6 to form a flaring mouth for facilitating the engagement of the clamp with the lid of the box. The inner or lower side or jaw of the U-shaped clamp is connected with the upper end of the brace by a spring bend 7, arranged in substantial parallelism with the inner side or jaw of the clamp and spaced therefrom forming with the same an approximately U-shaped loop. 80 The U-shaped spring bend or doubled portion, although shown at the front face of the lid in Fig. 1 of the accompanying drawings, may of course be arranged to engage the lid at the rear face thereof. The single side or 85 jaw of the upper crank will then be arranged at the front face of the lid of the box. The slight bending of the single side will enable the clamp to engage the lid of the box in either direction.

95 The lower clamp 3 consists of an outer depending jaw 8 and an inner jaw 9, extending longitudinally of the brace and projecting downward beyond the plane of the outer jaw and connected at its inner end with the outer jaw by a transverse top portion 10. The wire is bent upon itself to form the loop of the lower jaw, and is bent upward closing the inner side of the brace and is then bent 100 downward to form the connecting top portion 10. The outer jaw 8, which is located opposite the inner end of the loop or inner jaw, is straight and extends downwardly from the outer end of the top portion 10. The inner projecting jaw 9, which fits against 105 the inner face of the end 4 of the box, is provided with spurs or projections 11, formed

2 by upsetting the metal and extending from the inner engaging face of the inner jaw and adapted to be embedded in the material of the box. The spurs or projections 11 in 5 instead of being formed integral with the inner jaw 9 of the lower clamp may be applied to the same by means of a separate piece of metal in any preferred manner, as the inner jaw may be equipped with any form of spur 10 or projection for enabling it to grip the inner face of the end of the box.

In applying the device to the box, the downwardly projecting inner jaw 11 with its spurs or projections laterally offset the 15 upper portion of the brace from the vertical plane of the end 4 of the box, and it is necessary to flex or bend the brace between the clamps to engage the upper clamp with the lid 5. This bending or flexing of the brace 20 places the device under tension and causes the upper and lower clamps to firmly and positively grip the lid and the body of the box, which are rigidly connected by the device. The bending of the brace is facilitated 25 by the resiliency of the material and also by the connecting spring bend 7 at the upper end of the brace. This rigid connection between the lid and the body of the box enables the box to be handled by the lid in re- 30 moving the box from a show case and in replacing it therein, or in handing the box to a customer, and there is no liability of the box breaking away from the lid and producing an injury to its contents.

35 Having thus fully described my invention, what I claim as new and desire to secure by Letters Patent, is:—

1. A box lid holder including a straight inclined brace, a clamp arranged at the upper 40 end of the brace for engaging the lid, a lower clamp arranged at the lower end of the inclined brace for engaging the box, said lower clamp being provided with means for deflecting the upper end of the brace outwardly be- 45 fore the said upper clamp is connected with the lid, whereby when the upper clamp is engaged with the lid the brace will be flexed longitudinally and the lower clamp forced tightly into engagement with the box.

50 2. A box lid holder including an inclined brace, a lid-engaging clamp arranged at the upper end of the brace, and a box-engaging clamp located at the lower end of the brace

and composed of inner and outer jaws, the inner jaw being extended beyond the plane 55 of the outer jaw and arranged to deflect the upper end of the brace outwardly before the upper clamp is applied to the lid, whereby when the said upper clamp is engaged with the lid the brace will be flexed longitudinally 60 and will force the extended inner jaw firmly into engagement with the box.

3. A box lid holder including an inclined brace, a lid-engaging clamp arranged at the upper end of the brace, and a box-engaging 65 clamp located at the lower end of the brace and composed of inner and outer jaws, the inner jaw being extended longitudinally of the brace beyond the plane of the outer jaw and provided with one or more spurs or pro- 70 jections for engaging the box.

4. A box lid holder including an inclined brace, a lid-engaging clamp arranged at the upper end of the brace, and a lower box-engaging clamp arranged at the lower end of 75 the brace and consisting of an inner loop ex- tending longitudinally from the brace, a de- pending outer jaw located opposite the inner end of the loop, and a top portion connecting the inner and outer jaws.

80 5. A box lid holder including an inclined brace, a lid-engaging clamp arranged at the upper end of the brace, and a lower box-engaging clamp composed of inner and outer jaws and formed by bending the material 85 back upon itself to form a loop and extending the said material across the top of the brace and then bending the terminal portion down- ward to form the outer jaw.

6. A box lid holder including an inclined 90 brace, an upper resilient lid-engaging clamp disposed transversely of the brace, a spring bend connecting the upper clamp with the upper end of the brace, and a lower box-engaging clamp composed of an inner loop dis- 95 posed longitudinally of the brace, and a straight outer depending jaw located oppo- site the inner end of the loop and connected with the top of the same.

In testimony, that I claim the foregoing as 100 my own, I have hereto affixed my signature in the presence of two witnesses.

HENRY WILSON MORROW.
